UNITED STATES PATENT OFFICE.

CARLETON W. NASON, OF NEW YORK, N. Y., AND CHARLES YINGLING, OF METUCHEN, NEW JERSEY; SAID NASON ASSIGNOR TO SAID YINGLING.

ROCKING GRATE FOR FURNACES.

SPECIFICATION forming part of Letters Patent No. 644,365, dated February 27, 1900.

Application filed July 12, 1894. Serial No. 517,284. No model.

To all whom it may concern:

Be it known that we, CARLETON W. NASON, of the city and county of New York, in the State of New York, and CHARLES YINGLING, of Metuchen, in the county of Middlesex and State of New Jersey, have invented a certain new and useful Improvement in Rocking Grates for Furnaces, of which the following is a specification.

Our improved grate may be used in furnaces generally. It is well adapted for furnaces of upright steam-boilers, and we will describe it as thus applied.

The accompanying drawings form part of this specification and represent what we consider to be the best means of carrying out the invention.

Figure 1 is a plan view of a furnace-base with a grate therein embodying our new improvements. Fig. 2 is a vertical section of the same, partly in elevation; and Figs. 3 and 4 are views, on a larger scale, of the grate detached, Fig. 3 being a plan and Fig. 4 a vertical section on line 4-4 of Fig. 3.

Similar letters of reference indicate corresponding parts in all the figures where they appear.

Referring to the figures, A is the cast-iron base of a furnace for a steam-boiler, which boiler (not shown) may be an ordinary upright boiler or may be of any other form requiring a circular grate.

B is a shaft supported in bearings in the base A.

D is a circular rim turning on the shaft B. It is supported in a horizontal position on one side by a fixed stop A', cast on the base. The other side is supported by a movable stop C in the form of a sliding bolt. On drawing out this bolt the rim D may be tilted by any sufficient force and thrown into the inclined position shown in dotted lines in Fig. 2.

The rim D is cast with eight pockets d a little within the rim, each presenting an open-topped slot adapted to receive a pivot of a section of grate and to form an open-top bearing for said pivot.

The central shaft B engages in holes in the base A and extends a squared end outward to receive a suitable lever (not shown) by which the grate-sections can be rocked, while

the rim is stiffly held in the level position by the bolt C, or may be tilted by a further movement in the proper direction when the bolt C is pulled out. The rim engages on this shaft by 55 slots d', opening downward.

The central section of the grate is formed by short fingers B', cast on the central shaft B and having their plane top sufficiently far above the axis of turning (to wit, the axis of 60 the shaft B) to give horizontal as well as vertical movements to said tops when the shaft B is rocked. This shaft is also provided with segments of gears B² B². (See Figs. 3 and 4.) E and F are shafts of less length and of a little 65 less diameter supported by their extreme ends in open-top bearings in the pockets d which are nearest the center. G and H are still shorter shafts supported in open-top bearings in the pockets d which are farthest from the center. 70 Each of these four shafts is provided with short fingers E' F' G' H', respectively, and the plane tops of these fingers are sufficiently far above their corresponding axes of turning to give horizontal as well as vertical movements 75 thereto when the grate-sections formed by said fingers and their shafts are rocked. To impart this rocking motion, the shafts E F have each a tooth E² F², respectively, which engages one of the gear-segments B² on the shaft 80 B to receive motion, and a gear-segment E³ F³, respectively, which is engaged by a tooth G² H², respectively, on the shafts G and H. These teeth and gear-segments are formed integral with the corresponding shafts and underlie the fingers on such shaft. When, therefore, the grate-section B B' is rocked, the motion is imparted by the gear-segments and teeth to the parallel sections E E', F F', G G', and H H', the adjacent sections being 90 rocked in opposite directions. The fingers on adjacent sections are interleaved, (see Figs. 1 and 3,) and when the sections are rocked the so-interleaved fingers rise and fall together; but their lateral motion is in opposite 95 directions. As the tops of the sections are plane, (flat, in other words,) the fuel is lifted at each rise of the interleaved fingers, while at the same time, owing to the lateral motion of the fingers in opposite directions, the fuel 100 is torn apart with a shearing action which is well adapted to reduce any cinders to powder.

Should a cinder or coal be caught by the end of a finger as it descends, the open-top bearings of the corresponding shaft allow the grate-section to rise, so that the coal or cinder may pass downward.

At the edge of the gate the rim D may have short fingers D' thereon projecting inward and alternating with the fingers G' H', respectively, on the outer side of the shafts G H.

10 Modifications may be made without departing from the principle or sacrificing the advantages of the invention. We have shown (see Fig. 3) the central shaft B as geared to the immediately-adjacent shafts E and F on each side at two points, and each shaft E F is geared to the adjacent shaft G or H at only one point. Such arrangement is preferable, because the strain to be communicated from the shaft B to each shaft E and F is obviously greater than that from the shaft E or F to the corresponding shaft G or H; but there may be two or more segments gearing each of the shafts to the next, or one alone may serve at each place.

25 We claim as our invention—

1. In a grate, rotatory parallel sections having substantially-plane tops sufficiently far above the axes of turning to give horizontal as well as vertical movements to said tops

and interleaved fingers B' E' F' as shown, in 30 combination with means for rocking the adjacent sections in opposite directions so that the interleaved fingers move up and down together but laterally in opposite directions, substantially as described.

2. In a grate, a supporting-frame having open - top bearings, in combination two or more parallel sections mounted on axes supported in such bearings with provisions for rocking said sections, the said sections having substantially-plane tops adapted to serve as fuel-supporting surfaces and arranged so far above the axes that the motion induced by rocking shall not only tilt the sections but also move the tops horizontally, and a section being allowed to rise when a cinder or coal is caught by the end of a finger and thus permit, when required, the passage downward of such masses, substantially as described.

35 In testimony that we claim the invention above set forth we affix our signatures in the presence of two witnesses.

CARLETON W. NASON.
C. YINGLING.
